CONVERTIBLE CHAIR AND TABLE

Ruby S. Vellá, Los Angeles, Calif., assignor of one-half to Frank J. Burnham, Los Angeles, Calif.

Application May 2, 1950, Serial No. 9,629

Term of patent 14 years

(Cl. D15—8)

To all whom it may concern:

Be it known that I, Ruby S. Vellá, a citizen of the United States, residing in the city and county of Los Angeles and State of California, have invented a new, original, and ornamental Design for a Convertible Chair and Table, of which the following is a specification, reference being had to the accompanying drawing, forming part thereof.

Fig. 1 is a perspective view of a convertible chair and table adjusted to the chair position, showing my new design.

Fig. 2 is a side elevation, on a reduced scale, of the chair shown in Fig. 1 adjusted to the table position.

Fig. 3 is a front elevation of the table shown in Fig. 2.

Fig. 4 is a top plan view as indicated by the line 4—4 in Fig. 3.

I claim:

The ornamental design for a convertible chair and table, substantially as shown.

RUBY S. VELLÁ.
